George E. Raymond,

Edward Daygar,

By

UNITED STATES PATENT OFFICE.

GEORGE E. RAYMOND, OF GRAND RAPIDS, MICHIGAN.

VEHICLE-SPRING.

SPECIFICATION forming part of Letters Patent No. 412,665, dated October 8, 1889.

Application filed June 15, 1889. Serial No. 314,390. (No model.)

To all whom it may concern:

Be it known that I, GEORGE E. RAYMOND, a citizen of the United States, residing at the city of Grand Rapids, in the county of Kent 5 and State of Michigan, have invented certain new and useful Improvements in Vehicle-Springs, of which the following is a specification.

This invention relates to a spring-connection to the body of a vehicle, and to arms which are designed in whole or in part to support the vehicle-body, and particularly relates to improvements in the vehicle-spring described in the patent issued to George E. Raymond & Co., June 4, 1889, as sole assignee of Silas H. Raymond; and the invention consists in the use of bent or curved spring in combination with other parts fully described herein-after, the object being to simplify the construction referred to in said patent. This object I accomplish by means of the mechanism illustrated in the accompanying drawings, in which—

Figure 1 is a longitudinal sectional view of my newly-invented spring through the center of the line of attachment of such spring to the vehicle-body. Fig. 2 is a side elevation showing a preferred form of spring which I design to use. Fig. 3 is a modified form of 25 the parts shown in Fig. 1. Fig. 4 is another modified form of the same parts, and Fig. 5 shows a bottom view of a portion of a vehicle-body with a single spring.

Similar letters refer to similar parts throughout the several views.

C represents a portion of the vehicle-body. D represents the spring, curved between the point of attachment to the body and the center of the spring for the purpose of allowing 35 said spring to be acted upon by the weight of the vehicle-body and in order to obviate the necessity of a movable shackle attachment for the spring. The spring D is bolted or riveted directly to the vehicle-body or timbers attached to the body, as shown in the drawings by A A. It then curves a sufficient distance to allow the spring to play freely without any movement at the point of attachment to the body.

40 H H represent two arms supported at points B B to the side rail of the vehicle. These

arms are pivoted to the body or timbers connected to the body at the point E E.

In Fig. 1, K K represent sliding shackles, each pivoted at the lower end to the inner 45 end of the arms H H, and adapted to have a sliding movement upon the spring D, the object being to allow the inner ends of the arms to move to and from each other as the spring is pressed upon from above.

60 In Fig. 3, K' represents a single shackle having two links L and L'. Each of these links is pivoted to the stationary shackle K' and to the end of the arms H. It will readily be seen that in this construction the links L and L' will allow for the free movement of the arms H H.

In the modified form shown in Fig. 4 the shackle K² is made preferably stationary with 65 relation to the spring D, and is provided with a bolt P. The arms H H are slotted, as shown by S S, and are made to lap by each other, so that the bolt P passes through the shackle K² and through the slots in the inner ends of the arms. This construction allows for the free 70 movement of the inner ends of the arms H H. The form of attachment of the inner ends of the arms to the spring is not material, so long as those ends of the arms have a free movement, so as not to interfere with the free 75 movement of the spring.

The general shape or form of the spring D may be varied; but in order to have it work freely it must be curved sufficiently to allow 80 for the vertical movement of the shackles and the inner ends of the arms H H; otherwise it would be necessary to attach the spring to the body of the vehicle by means of movable 85 bearings, which necessity it is my object to obviate.

90 The spring may be made of a single piece of metal or several pieces; or several pieces of spring metal may be placed side by side and attached together so as to form a spring. The form of the spring-bars is immaterial so long 95 as the spring spans the space between the points of attachment to the vehicle-body and are bent or curved to allow a free movement without movement at the point of attachment to the vehicle-body.

100 I do not claim, broadly, the combination of the vehicle-body and the arms supported at

their outer ends by side bars, and a spring attachment at each end of the body, near the outside thereof, and spanning the space between such connecting points, for the purpose 5 of supporting the body of the vehicle, as I understand such invention is broadly claimed in the patent hereinbefore referred to.

Having thus described my invention, what I claim to have invented, and desire to secure 10 by Letters Patent, is—

In a vehicle, the combination of the vehicle-body, arms supported at their outer ends by side bars, a spring attached at each end to the body, near the outer side thereof, by a 15 rigid attachment to the body and spanning the space between such points of attachment, said arms pivoted near the center of each

arm to the body, and at their inner ends connected to the spring near the center of such spring, said spring having a curved form on either side of its center, and adapted to allow for the vertical movement of the center of the spring and the inner ends of the arms without moving the ends of said spring at the point of attachment to the vehicle-body, substantially as described.

In witness whereof I have hereunto set my hand and seal in the presence of two witnesses.

GEORGE E. RAYMOND. [L. S.]
